UNITED STATES PATENT OFFICE.

LYMAN C. JOSEPHS, JR., OF SCHENECTADY, NEW YORK, ASSIGNOR TO GENERAL ELECTRIC COMPANY, A CORPORATION OF NEW YORK.

DISTRIBUTING DEVICE.

1,164,286.

Specification of Letters Patent. Patented Dec. 14, 1915.

Application filed November 25, 1914. Serial No. 874,071.

To all whom it may concern:

Be it known that I, LYMAN C. JOSEPHS, Jr., a citizen of the United States, residing at Schenectady, in the county of Schenectady, State of New York, have invented certain new and useful Improvements in Distributing Devices, of which the following is a specification.

My invention relates to a distributing device, and particularly to such a device designed for the sanding of railway tracks.

Sanding devices are commonly employed in locomotives and cars for the ready application of sand, stored in a convenient receptacle, to the tracks, in order to increase the frictional grip of the wheels. The receptacles employed for the sand are usually constructed with a hopper-shaped bottom, and when the quantity of sand is considerable, or the sand is damp, there is a tendency toward caking or packing which prevents or hinders the operation of the device. I have, accordingly, so constructed my device that it will operate successfully under all conditions of service, and the object of my invention is to devise a distributing device, adapted for use as a locomotive sander, which shall be certain in operation and of a durable construction.

Another object of my invention is to devise means, applicable to a motor-operated device of this type, for preventing the introduction of sand to the motor bearings. Still another object is to construct a device of the type described so that wasting of the sand will not result from the vibration of the locomotive.

I preferably construct my device in the form of a casting capable of attachment to any desired type of receptacle. A hopper-shaped upper portion has an outlet in one side near the lower end. Communicating with this outlet is a passageway leading first in a general horizontal direction over a transverse ridge, formed by an upward bend, and thence downwardly for connection to a hose or pipe. Substantially opposite the outlet is a bearing for a plunger which is provided with an agitator and is movable toward and away from the outlet, for the purpose of pushing the sand through the passageway and across the ridge therein. I then provide a motor for operating the plunger, and preferably this motor will take the form of a fluid operated reciprocating engine, which

will commonly be operated by compressed air. A nozzle is arranged in the vertical portion of the outlet passageway, beyond the ridge, and an air passageway provided connecting the exhaust of the motor with this nozzle. A trap chamber is arranged intermediate the plunger bearing in the hopper-shaped casting and the bearing for the plunger in the motor, and this chamber communicates at its lower side with the air passageway.

In the accompanying drawing, wherein I have shown the preferred form of my invention, Figure 1 is a vertical cross-section showing the complete device as attached to a receptacle. Figs. 2 and 3 are cross-sections of the motor, showing the piston in various positions.

The larger portion of my device will preferably be constructed in the form of an integral casting, which is shown as provided with a hopper 10 designed for attachment to the lower end of any form of receptacle A. At the lower end of this hopper a slight recess 11 is provided, and at the side of this recess is the outlet 12. Extending in a substantially horizontal direction from the outlet is a passageway 13, and this passageway is provided with a ridge 14 extending transversely thereof, and conveniently formed by an upward bend of the passageway. Beyond this ridge the passageway proceeds in a general downward direction, and is adapted at its lower end 15 for connection to a hose or pipe. Substantially opposite the outlet 12 the recess 11 is provided with a bearing 16 for the horizontally reciprocable plunger 17, which may be moved toward and away from the outlet opening, thereby pushing the sand through the passageway 13. This plunger is provided with an agitator 18 extending upwardly into the hopper 10 to prevent caking of the sand. In the vertical portion of the passageway 13 a nozzle 19 allows for the introduction of a blast of air, which is led to the nozzle by means of the passageway 20.

For the reciprocation of the plunger, I provide a suitable motor 30, which shall preferably be constructed as a fluid-operated device, and will comprise a main cylinder 31 within which the piston 32 reciprocates, this piston being here shown as integrally connected with the plunger 17. The piston is constructed with a port 33

running longitudinally thereof, and in the cylinder 31 is an exhaust port 34, connected with the air passageway 20. As is here shown, this motor may be detachably secured, by means of bolts, to the main casting. Detachably secured to the cylinder 31 is a valve casing 35 provided with an inlet 36. In this casing a valve 37, mounted on an extension 38 of the piston, controls the admission of air to one side or the other of the piston. Movement of this valve, which is constructed in the form of a perforated disk, is limited by means of shoulders 39 and 39' on the piston extension, and by a metallic gasket 41 bolted between the cylinder 31 and the valve casing 35.

Intermediate the bearing 16 in the main casting and the bearing for the plunger in the cylinder of the motor, I have provided a trap chamber 40 which communicates at its lower end with the air passageway 20.

In operation, when air is supplied to the motor the plunger 17 will be reciprocated within the recess at the lower end of the hopper 10, and thereby intermittently push the sand through the outlet into the passageway 13. By continued movement of the plunger, the sand will be forced past the ridge 14 in the passageway and will drop by gravity to the outer end thereof; from here on its progress will be aided by the blasts of air admitted through the nozzle 19. Any tendency of the sand to cake will be prevented by the agitator 18 and by the forcing action of the plunger 17.

Reciprocation of the plunger is secured by the action of the air operated motor. In the position shown in Fig. 1, the piston has just finished its travel to the left, and, by means of the shoulder 39', has pushed the valve 37 past the inlet opening 36. Incoming air will thereupon force the valve over against the shoulder 39, as shown in Fig. 2, and will at once move the piston to the right. The design is such that cut off will occur at about 95 per cent. of the stroke, and, due to the momentum of the device, the piston will carry the valve past the port, and is shown in Fig. 3 as having reached the limit of its movement to the right. As will be seen from an inspection of this figure, movement of the valve 37 to the right is prevented by the gasket 41 and the continued supply of air through the inlet 36 will now pass through the longitudinal passage 33 to the right-hand side of the piston and produce movement of the piston to the left.

As shown in the drawings, the exhaust port 34 is so located that it will be opened by movement of the piston after cut off has occurred, and the continued expansion of the air will send a blast through the passage 20 to the nozzle 19, and assist in forcing out the sand. In order to prevent injury to the motor bearings, and, if possible, en-

trance of sand within the motor cylinder, I have provided the trap chamber 40 intermediate the bearing 16 in the main casting and the bearing for the plunger in the motor casing. As a consequence, any sand which is drawn through the bearing 16 by continued reciprocation of the plunger will fall into the chamber 40, and because of its connection with the air passage 20 will be blown out therefrom.

If the quantity of sand in the hopper is small, and it happens to be dry, then the vibration of the locomotive will tend to make the sand rattle out of the hopper through the passageway. With my device, however, the ridge 14 will act as a trap, and practically prevent this loss. It will be seen, then, that my device is equally applicable for use with wet or dry sand, and in large or small quantities.

Although I have herein illustrated and described my device as a locomotive sander, I conceive that it might be equally useful for other purposes wherein it is desired to secure a positive distribution of a finely divided material from a receptacle. I, accordingly, do not wish to be limited to this particular application of my device. Furthermore, I conceive that various modifications of the particular arrangement herein shown might be made, and I, therefore, seek to cover in the appended claims all such modifications which come within the true scope and spirit of my invention.

What I claim as new and desire to secure by Letters Patent of the United States, is:—

1. A distributing device comprising a receptacle having an outlet near its lower end, a passageway leading from said outlet at an angle to the vertical axis of said receptacle, means movable toward and away from said outlet for intermittently forcing the contents of said receptacle through said passageway, and a nozzle in said passageway adapted for the introduction of a blast of air to assist in dispensing said contents.

2. A distributing device comprising a receptacle having an outlet near its lower end, a passageway leading from said outlet at an angle to the vertical axis of said receptacle, a ridge across the lower side of said passageway, means movable toward and away from said outlet for intermittently forcing the contents of said receptacle through said passageway and across said ridge, and a nozzle in said passageway beyond said ridge adapted for the introduction of a blast of air to assist in dispensing said contents.

3. A distributing device comprising a receptacle having an outlet near its lower end, a passageway leading from said outlet in a substantially horizontal direction and provided with an upward bend intermediate its ends, means movable toward and away from

said outlet for intermittently forcing the contents of said receptacle through said passageway and beyond said bend, and a nozzle in said passageway beyond said bend adapted for the introduction of a blast of air to assist in dispensing said contents.

4. A distributing device comprising a receptacle having an outlet, a plunger movable toward and away from said outlet for intermittently forcing the contents of the receptacle through said outlet, a motor for operating said plunger, a bearing for said plunger in said receptacle, another bearing for said plunger, and a trap chamber intermediate said bearings.

5. A distributing device comprising a receptacle having an outlet, a plunger movable toward and away from said outlet for intermittently forcing the contents of the receptacle through said outlet, a passageway leading to a point adjacent said outlet and adapted for the introduction of a blast of air to assist in dispensing said contents, a motor for operating said plunger, a bearing for said plunger in said receptacle, another bearing for said plunger, and a trap chamber intermediate said bearings, said trap chamber opening into said passageway.

6. A distributing device comprising a re-

ceptacle having an outlet, a plunger movable toward and away from said outlet for intermittently forcing the contents of the receptacle through said outlet, a fluid-operated motor for operating said plunger, a nozzle adjacent said outlet, and a passageway connecting the exhaust of said motor and said nozzle.

7. A distributing device comprising a receptacle having an outlet near its lower end, a passageway leading from said outlet in a substantially horizontal direction and provided with an upward bend intermediate its ends, a nozzle in said passageway beyond said bend, a plunger movable toward and away from said outlet, a bearing for said plunger in said receptacle, a fluid operated motor for moving said plunger, a bearing for said plunger in said motor, a trap chamber intermediate said bearings, a passageway connecting the exhaust of said motor with said nozzle, said chamber opening into said last mentioned passageway.

In witness whereof, I have hereunto set my hand this 24th day of November, 1914.
